ATTORNEY

UNITED STATES PATENT OFFICE

RALPH ST. LAWRENCE PEVERLEY, OF CHESTER, ENGLAND, ASSIGNOR TO H. H. ROBERTSON COMPANY, OF PITTSBURGH, PENNSYLVANIA, A CORPORATION OF PENNSYLVANIA

FRAME FOR WINDOWS, SKYLIGHTS, AND THE LIKE

Application filed November 5, 1928, Serial No. 317,263, and in Great Britain November 10, 1927.

This invention relates to improvements in frames for windows, skylights and the like comprising metal frames having ledges or flanges projecting from ribs forming the 5 sides of the frame so as to provide seatings on which sheets of glass can be supported and is applicable to such frames in which the ribs are also provided with exterior ledges or flanges having surfaces of a suitable contour 10 to conform closely to the surface shape of a sheet of corrugated, beaded, ridged or like material around an aperture in the sheet into which the frame is inserted.

According to this invention, on the inner 15 side of the frame, at one end thereof, a condensation gutter is provided so that water collecting by condensation on the inside or underside of the glass after trickling down the same will be caught in the gutter. Holes 20 are provided through the vertical rib of the frame allowing the water collecting in the gutter to pass out through this rib on to the exterior of the roof in which the frame is inserted.

As a further feature of the said invention 25 the flange within the ribs of the frame and on which the glass is supported, is arranged in a plane oblique to the flanges on the outsides of the ribs in order that the surface of the 30 glass may be brought above or beyond the crests of the corrugations or ribs in the sheet in which the frame is inserted. Thus, the rib does not provide any step or ledge at the lower edge of the glass serving as a trap to 35 collect sediment deposited by rain flowing over the outer surface of the glass. Suitable lugs are provided, for example, at or near the ends of the lower rib in order to prevent the glass sliding from its seat. With this arrangement the lower edge of the glass can 40 be made to extend beyond the lower rib so as to form an eaves above the outlet holes provided in the lower rib for the escape of water from the gutter, this eaves serving to prevent 45 rain driving in through these holes.

In the accompanying drawing which shows how the said invention may be conveniently carried into practice:—

Figure 1 is a plan view of a frame constructed in accordance with this invention.

Figure 2 is an end view thereof and Figures 3, 4, 5, 6 and 7, show sections taken on the lines 3—3, 4—4, 5—5, 6—6 and 7—7 respectively and drawn to a larger scale.

As shown in the drawing the sides and ends 55 of the frame comprise ribs *a* having on their outer side flanges *b* and *c* which are curved to fit closely on or be secured upon the ridges or in the grooves of a corrugated sheet to which the frame is to be attached. The side 60 flanges *b* are corrugated in the direction of their length (Figure 1) and the flanges *c* are corrugated in a direction transverse to their length as shown in Figure 2, the said ribs being provided with holes *d* to facilitate the 65 frame being riveted or bolted in the aperture in the corrugated sheet. The frame may however be secured in the aperture in the corrugated sheet by electric or spot welding, or in any other convenient manner. On the in- 70 side of the ribs *a*, flat flanges *e* are provided as a bed or support for the glass or sash to be held therein.

On the inner side of the frame at one end 75 thereof, a condensation gutter *f* is provided so that water collecting by condensation on the under side of the glass will trickle down the same and be caught in the gutter. The gutter *f* is formed integrally with a part *a'* of the vertical rib *a* which projects down- 80 wardly from the flanges *e* of the frame. Holes *g* are provided through the vertical rib part *a'* of the frame allowing the water collecting in the gutter to pass out there-through on to the upper side of the flange *c* adjacent 85 the part *a'*.

The flanges *e* extending longitudinally of the frame are arranged in a plane oblique to the flanges *b* (Figures 7 and 8) and thus the glass may be extended above the crests of the 90 corrugations or ribs of the flange *c* adjacent the gutter *f*. In order that the glass may be retained in position the ribs *a* are extended across the flange *c* and are provided with lugs *h* against which the glass may rest. The part 95 of the glass extending above the flange *c* will form an eaves above the outlet holes *g* to prevent rain from driving in through these holes.

The frame is shown constructed with the 100

ribs, and interior and exterior flanges comprised in a unitary structure but if desired the frame may be made of separate parts secured together in any suitable manner.

I claim:

- 5 1. In a frame for windows, skylights or the like comprising ribs forming the sides of the frame, the provision of a gutter for collecting the water formed by condensation upon the inside or underside of a sheet or sheets of glass arranged within the frame.
- 10 2. A frame for windows, skylights or the like as claimed in claim 1, in which the gutter is formed integrally with the ribs forming the side of the frame.
- 15 3. A frame for windows, skylights or the like as claimed in claim 1, wherein flanges project on the exterior of the rib to support the frame in an aperture in a roof or the like.
- 20 4. A frame for windows, skylights or the like as claimed in claim 1, in which the sheet or sheets of glass are supported on flanges projecting upon the interior of the ribs to form a seating for the glass.
- 25 5. A frame for windows, skylights and the like as claimed in claim 1, wherein the water collecting in the gutter is conveyed to the upper surface of an exterior flange through holes in the rib adjacent the gutter.
- 30 6. A frame for windows, skylights and the like as claimed in claim 1, in which the glass is supported on flanges projecting from the interior of the ribs and arranged in a plane oblique to flanges projecting from the exterior of the ribs in order that the glass may project over the gutter and the exterior flange adjacent the gutter to form an eaves.
- 35 7. A frame for windows, skylights and the like as claimed in claim 1, in which the glass is retained in position above the gutter by lugs on the ribs.

RALPH ST. LAWRENCE PEVERLEY.
